VIBRATORY MOTOR FOR THERAPEUTIC DEVICE
Gene M. Neff, Racine, Wis., assignor to John Oster Manufacturing Co., Milwaukee, Wis., a corporation of Wisconsin

Filed July 31, 1958, Ser. No. 752,275
1 Claim. (Cl. 310—29)

This invention relates to vibratory therapeutic cushions and has as its purpose to provide an improved device of this type which is capable of being sold at a relatively modest price, and yet is highly effective and achieves certain improved results not heretofore obtained with such cushions.

One of the more specific objects of this invention is to provide a device of the character described wherein the vibration producing motor unit is fully and directly encapsulated in a soft, resilient body molded of sponge rubber or, more desirably, of urethane foam.

Another object of this invention is to provide a vibratory therapeutic cushion having a motor unit of simplified and improved construction which includes a housing having opposite substantially flat walls, one of which is considerably larger in area than the other, and which walls underlie the opposite sides of the cushion and define the vibration transmitting areas thereof, so that one side of the cushion has a relatively large massage area for general utility, and the other side thereof has a smaller massage area for localized application.

Still another object of this invention resides in the provision of a vibrating motor of the type having a solenoid wound on a permeable core and cooperable with an armature, wherein the armature is fixed to a substantially rigid wall portion of a member comprising part of a housing which encloses the motor, and wherein all of the vibratory motion occurs in the core and solenoid, which are resiliently mounted on the medial portion of a flexible strap, the ends of which are secured to said member.

In vibrator units of the character just described the space between the core and the armature is critical and must be carefully adjusted during assembly of the device. With this in mind, it is another object of the present invention to provide a structure wherein this adjustment may be very readily and accurately made during assembly.

With the above and other objects in view which will appear as the description proceeds, this invention resides in the novel construction, combination and arrangement of parts substantially as hereinafter described and more particularly defined by the appended claim, it being understood that such changes in the precise embodiment of the herein disclosed invention may be made as come within the scope of the claim.

The accompanying drawings illustrate one complete example of the physical embodiment of the invention, constructed according to the best mode so far devised for the practical application of the principles thereof, and in which:

FIGURE 1 is a perspective view of a vibratory therapeutic cushion made in accordance with this invention;

FIGURE 2 is a cross sectional view through the cushion;

FIGURE 3 is a plan view of the motor unit with part of its cover section broken away;

FIGURE 4 is a detail sectional view through FIGURE 3 on the plane of the line 4—4; and

FIGURE 5 is a disassembled perspective view of the motor unit with a portion of one housing member shown broken away.

Referring now particularly to the accompanying drawings, the numeral 3 designates the body of the vibratory therapeutic cushion of this invention. It is formed of

soft, pliable resilient material and has a motor unit 4 embedded therein. Preferably, the body 3 is encased in a removable cover 5 which may be formed of any suitable fabric or plastic material, and is detachably held in place by a zipper fastener 6.

The motor unit 4 comprises a motor 7 and a housing 8 in which the motor is mounted in such a way that the walls of the housing are vibrated by the motor and hence constitute the vibration transmitting members of the motor unit. The motor is adapted to be connected with a source of current by means of a cord 9 having an in-the-line control switch 10 connected therein. By means of this control switch, the motor may be turned on and off and controlled to provide either mild massage or more penetrating massage, through circuit means which are well known to those skilled in the art.

Specifically, the motor 7 comprises a field coil or solenoid 11 wound on a spool 12 which is fitted onto the middle leg 13 of an E-shaped laminated magnet core or frame 14. The core and solenoid cooperate with a U-shaped armature 16 formed of magnetically permeable substantially rigid metal.

The housing in which the motor is enclosed and by which its parts are supported, comprises a bottom plate 18 and a substantially bowl-shaped top member 19. The bottom plate 18 is generally rectangular in shape with rounded corners and with an upturned stiffening flange 21 extending about its perimeter. At its medial portion, the plate is dished downwardly in two circular, relatively shallow steps 22 and 23. Providing the plate 18 with the multiple stepped formation just described, reinforces and stiffens the same, and assures better transmission of vibration from the motor per se to the entire area of the plate 18. The plate is further stiffened and reinforced by a series of large and small flanged holes 26 and 27, respectively, formed in the plate, the flanges 26' and 27' at the peripheries of the holes providing the stiffening.

The bowl-shaped upper housing member 19 has a frustoconical side wall 28, a flat end wall 29 and a peripheral flange 30 which flatwise overlies the bottom plate around its dished central portion, and which is secured to the bottom plate by means of screws 31 and nuts 32. It will be observed that the bottom plate and the upper housing member cooperate to define an enclosure of which the lower dished step 23 in the bottom plate and the end wall 29 of the top housing member comprise a pair of opposing, spaced apart substantially rigid walls.

The U-shaped armature 16 is affixed, as by means of rivets 33 through its bight portion, to the top wall of the housing, extending diametrically thereacross with its legs 34 projecting downwardly; and consequently the armature is constrained against any motion relative to the housing.

The E-shaped core 14 is mounted for motion toward and from the armature by means of a resilient strap 36 which spans the interior of the housing, substantially parallel to the armature. The ends of the strap are clampingly secured between the flange 30 on the bowl-shaped upper housing member and the upper surface of the bottom plate, and may be held in place by two of the screws and nuts 31 and 32 that secure the two housing members together. The core is secured to the medial portion of the strap by means of a single screw 37 threaded thereto, and is held with its legs projecting toward the armature and its outer legs 38 aligned with but spaced from the legs 34 of the armature. The screw 37 which holds the core also passes through a channel shaped clip 39, the legs of which straddle both the strap and the core to prevent the latter from rotating about the screw 37.

Between each end of the strap and its medial portion to which the core is secured, the strap has a relatively large arcuately curved loop 40. These loops permit the

medial portion of the strap to flex up and down relative to its anchored end portions, and thus provide for movement of the core toward and from the armature. The medial portion of the strap is normally held spaced a substantial distance from the dished central portion 23 of the bottom plate, and it holds the core with the ends of its legs spaced from the legs of the armature, so as to permit the core to move freely up and down in response to electro-magnetic attraction between it and the armature. Spacing of the medial portion of the strap from the bottom plate is of course provided for by the concavely dished central portion 23 of the bottom plate, and in addition the bottom plate is bumped upwardly, as at 42, at the points where the screws which secure the strap pass through it.

One of the most important features of this invention results from the fact that the core 14 of the vibrator motor has substantial mass, at least as compared to that of the armature 16, and by further reason of the fact that the core is mounted on a medial portion of the resilient strap 36, in spaced relation to the housing walls. The core is thus movable relative to the housing, being substantially suspended therein by means of the resilient strap 36, so that its vibration cannot be damped by the weight of a person pressing down upon the housing during use of the device. In fact, the core will continue to vibrate at a frequency determined by the pulsating current supplied to the solenoid 11 during use of the device even though the full weight of a person is imposed upon the housing, whereas in many prior devices of this type it was possible to nearly stop the motor from vibrating by force applied to the housing thereof.

In assembling the vibrator motor of this invention, the strap, with the core secured to it, has its ends clamped to the flange 30 on the bowl-shaped upper housing member before the bottom plate is secured to the upper housing member. This clamping may be temporary, as by means of a suitable fixture which will be within the knowledge of those skilled in the art, or it may be permanent, as by means of riveting or spot welding. In any case, the preliminary securing of the strap to the bowl-shaped housing member permits the medial portion of the strap to be readily and accurately adjusted so that the outer legs 38 of the core will be spaced the correct distance from the legs 34 of the armature to insure optimum vibratory action. After this adjustment is made the upper housing member and the bottom plate can be fastened together.

Preferably, a pulsating unidirectional current is employed for energization of the motor and, to that end, 50 a selenium type rectifier 44 is provided. This unit is conveniently mounted upon the bottom plate 18 by being riveted thereto.

The supply cord 9 and, more particularly, the three leads 9 thereof which extend from the control switch to the motor and the rectifier, enter the motor housing through an access opening 45 formed in an indentation 46 in the upper housing member, and, although the leads 9 are not completely illustrated in FIGURE 3, it is understood that they are connected with the coil terminals and the rectifier in a well known manner.

From the foregoing description, taken in connection with the accompanying drawings, it will be apparent that this invention provides a vibratory therapeutic cushion, and more particularly a vibrator motor for therapeutic cushions and similar articles, which possesses many advantages and constitutes a substantial improvement over prior devices of this type, particularly in that the vibrator motor is constructed of simple and inexpensive parts and is easy to assemble, and in that it may be very readily and accurately adjusted during the assembly operation.

What is claimed as my invention is:

A therapeutic vibrator unit of the type comprising a housing, an armature in the housing, and a solenoid wound on a core in the housing and adapted to be energized with pulsating current to effect relative vibratory motion of the core and armature toward and from one another, said vibrator unit being characterized by the fact that: the housing includes a rigid substantially bowl-shaped member mounted for bodily substantially axial vibratory motion; the armature is stationarily secured to the bottom of the bowl-shaped member, at the interior thereof; and the core has substantial mass and is supported on the medial portion of an elongated strip of resilient material, the ends of which are anchored to the rim of the bowl-shaped member and which extends across the bowl-shaped member and has arcuately curved loop portions between each end thereof and its medial portion whereby its medial portion is held in a position in which the core is normally spaced from the housing walls and the armature but is movable relative to the housing at all times toward and from the armature in response to a pulsating current impressed upon the solenoid.
